(57) **CLAIM**

The ornamental design of a collapsible skylight tube having open ends and a light reflecting inner surface, as shown and described.

DESCRIPTION

FIG. 1 is a perspective view of a collapsible skylight tube having open ends and a light reflecting inner surface and showing our new design;

FIG. 2 is a side view thereof, the other three side views being the same;

FIG. 3 is a top view thereof, the bottom view being the same;

FIG. 4 is a perspective view of the collapsible skylight tube having open ends and a light reflecting inner surface shown in FIGS. 1-3 in its collapsed condition;

FIG. 5 is a perspective view of a second embodiment of our design;

FIG. 6 is an end view of the second embodiment, the opposite end view being the same;

FIG. 7 is a side view of the second embodiment, the opposite side view being the same;

FIG. 8 is a top view of the second embodiment, the bottom view being the same; and,

FIG. 9 is a perspective view of the collapsible skylight tube having open ends and a light reflecting inner surface shown in FIGS. 5-8 in its collapsed condition.
